John Maffren.
ATTORNEY

UNITED STATES PATENT OFFICE

ARTHUR CLAUD-MANTLE, OF TRUMBULL, CONNECTICUT, ASSIGNOR TO THE BASSICK COMPANY, OF BRIDGEPORT, CONNECTICUT, A CORPORATION OF CONNECTICUT

HOOD CATCH

Application filed April 14, 1931. Serial No. 529,901.

The present invention relates to improvements in hood catches, particularly for automobiles, and has for an object to provide a hood catch of the so-called inside fastening type which may be secured without the use of rivets, bolts and nuts, welding, or other such fastening means as have heretofore been employed. A further object is to provide fastening means which will enable the hood catch to be attached quickly and accurately, and which will reliably secure the same against looseness and rattling.

With the above and other objects in view an embodiment of the invention is shown in the accompanying drawing, and this embodiment will be hereinafter more fully described with reference thereto and the invention will be finally pointed out in the claims.

20 In the drawing:

Fig. 1 is a side elevation of a hood catch, according to the exemplary embodiment of the invention illustrated.

Fig. 2 is a plan view of the attaching means 25 in its form prior to assembly with the catch.

Fig. 3 is a sectional view along the lines 3—3 of Fig. 2.

Fig. 4 is a sectional view taken along the line 4—4 of Fig. 2.

30 Fig. 5 is a vertical sectional view showing the hood catch attached to the hood.

Fig. 6 is a rear elevation showing the hood catch attached to the hood.

Similar reference characters indicate corresponding parts throughout the several figures of the drawing.

Referring to the drawing, the hood catch shown by way of illustration comprises a frame, preferably formed of sheet metal, consisting of spaced parallel side portions 10 and an angularly disposed base portion 11 connecting the side portions, the forward edges of the side portions being recessed at their lower forward edges portions as at 12, for co-operating with the fastening means, as will

hereinafter more fully appear. Ears 13 are bent outwardly from the projecting forward edges of the side portions above said recesses 12 and are secured to the inner side of the face plate or escutcheon 14, preferably by 50 spotwelding.

The face plate is provided with a vertically disposed inwardly flanged slot 15, registering with the space between the side portions of the frame, the upper end of the slot being below the upper end of the frame and the lower end being above the recesses 12. The periphery of the base plate is flanged, as at 16, so that it engages snugly against the face of the hood. While any suitable catch element may be employed I have illustrated an exemplary one comprising a handle portion 17 projecting through the slot 15 and a shank or bolt portion 18 extending downwardly through a slot 11^a in the base of the frame, the handle being provided at its inner end with a fulcrum pin 19 having its projecting ends engaged for vertical movement in vertical slots 20 provided in the side portions of the frame. A washer 21 is provided upon the shank in engagement with the inclined base 11 of the frame and between this washer and the shoulder of the handle portion a helical spring 22 is provided about the shank which exerts an upward force 60 on the catch lever.

The lower end of the shank is bent inwardly and slightly upwardly providing a recess 23, and is then bent downwardly providing a camming surface 24. The catch is adapted to engage a horizontal bar 25 secured to any suitable support upon the automobile frame, and for instance, the front of the cowl for the rear catch and the radiator support for the front catch.

85 The side portions of the frame are provided near their upper ends and in line with the recesses 12 with rectangular apertures 26, for cooperation with the fastening means, as will presently more fully appear.

The hood 27, to which the catch is attached is provided with a vertical slot 28 through which the frame is adapted to be passed to the inner side of the hood, the face plate engaging the outer side and the upper ends of the recess 12 engaging the lower wall of the slot 28.

The fastening means comprises a clamping plate consisting of side legs 29—29 connected at their lower ends by a bendable bar portion 30. The inner edges of the side legs are provided adjacent the bar portion 30 with projecting lugs portions 31 slightly beveled as at 32, adapted in the assembled relation to engage within the recess 12 of the frame, recessed portions 33 in spaced relation above the lugs 31, adapted in the assembled relation to provide clearance spaces for the ends of the fulcrum pin 19, and adjacent the upper edges with inwardly projecting lugs 34 having their end portions curved, as at 35, and beveled on the outer side, as at 36, and adapted in the assembled relation to be inserted in the apertures 26. As shown in Fig. 2 the clamping plate is in its form prior to assembly and it will be observed that the space between the side legs is such that it may be engaged from beneath of each side from the frame.

30 The apertures 26 and the recess 12 are so proportioned that in the assembled relation, as indicated in Fig. 5, they extend from a point forwardly of the inner surface of the hood to a point rearwardly thereof, the latter distance being substantially equal to or slightly less than the metal thickness of the clamping plate. The side lugs of the clamping plate are adapted to be swung inwardly through bending of the bar portion 30, the lugs 31 entering the recesses 12 and the lugs 34 entering the recesses 36 as indicated in Fig. 5, and the fit will preferably be such that the plate must be forced into place. In this relation the hood catch is securely and accurately assembled on the hood.

It will be observed that the beveled scope of the lugs 31 and 34 permit them to be forced into the recesses 12 and apertures 26 with a tight wedge fit.

50 I have illustrated and described a preferred and satisfactory embodiment of the invention, but it will be obvious that changes may be made therein, within the spirit and scope thereof as defined in the appended claims.

Having thus described my invention what I claim and desire to secure by Letters Patent is:—

1. In a hood catch, a frame adapted to be engaged in an opening in a hood, means connected to said frame adapted to engage the outer side of said hood, and fastening means adapted to engage said frame at the inner side of the hood through engaging movement parallel to the hood surface and cooperating

with said first mentioned means to secure the frame to the hood.

2. In a hood catch, a frame adapted to be engaged in an opening in a hood, means connected to said frame adapted to engage the outer side of said hood, and clamping means adapted to be interlocked with said frame at the inner side of the hood through engaging movement parallel to the hood surface and cooperating with said first mentioned means to 75 secure the frame to the hood.

3. In a hood catch, a frame adapted to be engaged in an opening in a hood, means connected to said frame adapted to engage the outer side of said hood, and fastening means 80 adapted to be bent into interlocking relation with said frame at the inner side of the hood and cooperating with said first mentioned means to secure the frame to the hood.

4. In a hood catch, a frame adapted to be 85 engaged in an opening in a hood, means connected to said frame adapted to engage the outer side of said hood, and fastening means adapted to wedgingly engage said frame at the inner side of the hood and cooperating 90 with said first mentioned means to secure the frame to the hood.

5. In a hood catch, a frame adapted to be engaged in an opening in a hood and having 95 side openings projected inwardly with respect to the inner surface of the hood, means connected to said frame adapted to engage the outer side of said hood, and fastening means at the inner side of the hood including 100 side portions adapted to be bent into said openings of the frame and cooperating with said first mentioned means to secure the frame to the hood.

6. In a hood catch, a frame adapted to be engaged in an opening in a hood and having 105 side openings projected inwardly with respect to the inner surface of the hood, means connected to said frame adapted to engage the outer side of said hood, and fastening means at the inner side of the hood comprising a 110 transverse bendable portion and side leg portions adapted to be bent into said openings of the frame and cooperating with said first mentioned means to secure the frame to the hood.

7. In a hood catch, a frame adapted to be engaged in an opening in a hood and having vertically spaced side openings projected inwardly with respect to the inner surface of the hood, means connected to said frame 120 adapted to engage the outer side of said hood, and fastening means at the inner side of the hood including side portions adapted to be bent into said openings of the frame and cooperating with said first mentioned means 125 to secure the frame to the hood.

8. In a hood catch, a frame adapted to be engaged in an opening in a hood and having side openings projected inwardly with respect to the inner surface of the hood, means 130

connected to said frame adapted to engage the outer side of said hood, and fastening means at the inner side of the hood comprising a transverse bendable portion and side leg portions having projecting lug portions adapted to be bent into said openings of the frame and cooperating with said first mentioned means to secure the frame to the hood.

Signed at Bridgeport, county of Fairfield, and State of Connecticut, this 14th day of March, 1931.

ARTHUR CLAUD-MANTLE.
